COMBINATION WINDOW AWNING AND
CASE STRUCTURE

John P. Francis, 20 Boston St., Haverhill, Mass. 01830
Continuation-in-part of design application Ser. No. 13,387,
Sept. 4, 1968. This application Nov. 3, 1969, Ser. No.
19,901

Term of patent 14 years

Int. Cl. D25—02
U.S. Cl. D13—1

FIG.1

FIG. 2

FIG.3

FIG.4

FIG.5

FIG.6

FIG. 1 is a perspective view of a combination window awning and case structure, embodying my new design,

FIG. 2 is a side elevation view, with the awning in a vertically spaced apart position above the case structure,

FIG. 3 is a side elevation view, wherein the awning has been moved downwardly, and repositioned on the case structure,

FIG. 4 is a perspective view of another form of the invention,

FIG. 5 is a side elevation view thereof, with the awning in a vertically spaced apart position above the case structure, and

FIG. 6 is a side elevation view thereof, wherein the awning has been moved downwardly, and repositioned on the case structure.

The window structure fragmentarily shown in broken lines in FIGS. 1 to 6 inclusive is included for illustrative purposes only.

This is a continuation-in-part of Design application Ser. No. D. 13,387, filed Sept. 4, 1968 now Design Pat. No. D. 216,103.

I claim:

The ornamental design for a combination window awning and case structure, substantially as shown and described.
